OVERSHOE-BOOT

Alfred E. Shaffer, Mishawaka, Ind., assignor to
 Mishawaka Rubber and Woolen Manufacturing Company, Mishawaka, Ind., a corporation of Indiana.

Application September 27, 1944, Serial No. 555,988

1 Claim. (Cl. 36—7.3)

1 My invention relates to a combination overshoe-boot type of footwear which is adapted to be worn optionally as a loose fitting boot or as a close fitting overshoe or galosh, the upper thereof, like that of an ordinary rubber boot, having no opening down the front or otherwise such as ordinarily provided in overshoes and galoshes to permit expansion of the upper for inserting the foot, but being circumferentially continuous and large enough to permit the foot to be readily inserted so that it is essentially a loose fitting boot and may be worn as such, the upper, however, being sufficiently flexible and arranged to be conveniently folded and secured in a form fitting manner so that it may also be worn as a form fitting overshoe or galosh if desired.

For this form fitting adaptation as an overshoe or galosh, a fastener, preferably of ornamental type, is employed for securing the upper in the folded close fitting form, said fastener being so arranged that it not only does not impair the utility or detract from the appearance of the overshoe-boot when used as a loose fitting boot but may serve as an ornamental feature thereof. Moreover, the top of the overshoe-boot is preferably formed in a manner to lend itself to the folding to the close fitting overshoe or galosh form and at the same time contribute style and attractiveness to the overshoe-boot both in the loose fitting boot and close fitting overshoe forms.

While the invention, or certain features thereof, may be used in connection with footwear of other types, this invention is designed particularly for use in waterproof footwear of the type that is ordinarily worn over shoes, and is particularly advantageous therein as it insures a thoroughly waterproofed structure as the foot and leg covering are continuous and unbroken and devoid of any openings, inserts, or the like which are difficult to seal and likely to cause leakage. Moreover, the invention provides an adaptability that is desirable in waterproof footwear as it is sometimes desirable to wear such footwear loosely in the manner of a boot and at other times in a neat snug fitting manner.

The principal objects of my invention are, to provide an improved article of footwear which is adapted to be worn optionally as a loose fitting boot or in a snug form fitting manner; to construct the footwear with a circumferentially continuous boot like upper which is large enough to permit insertion of the foot and is foldable to and fastenable in a snug form fitting form; to construct the upper so that it folds readily at the

selected location; to shape the upper at the top so as to facilitate the folding at the selected location and in a manner that contributes to attractiveness of appearance in both the loose fitting and the snug fitting forms; to provide fastening means for conveniently securing the upper in the folded form; to arrange the fastener so that it lends attractiveness to the overshoe-boot in both the loose fitting or snug fitting forms; and to provide a structure which lends itself to thorough waterproofing, and although devoid of any openings, inserts, or the like, such as are customarily employed in form fitting waterproof footwear to permit expansion for insertion of the foot, is contractable to a snug form fitting form in which immunity to leakage is assured—these and other objects being accomplished as more fully pointed out hereafter and as disclosed in the accompanying drawing in which:

Fig. 1 is a perspective view of a combination overshoe-boot constructed in accordance with my invention and shown in the loose boot like form in which it may be worn;

Fig. 2 is a similar view showing the overshoe-boot in the contracted form fitting form in which it may be optionally worn;

Fig. 3 is a sectional view of the overshoe-boot upper taken on the line 3—3 of Fig. 1 and showing also in section the form on which the overshoe-boot is constructed;

Fig. 4 is a sectional view of the overshoe-boot upper taken on the line 4—4 of Fig. 2 and showing the upper in the folded form fitting form;

Fig. 5 is an enlarged fragmentary section of the overshoe-boot upper taken on the line 5—5 of Fig. 1.

Referring to the drawing, which shows a waterproof overshoe-boot of the type to which the invention is particularly applicable and which is designed to be worn over the ordinary shoes, the reference numeral 6 indicates the foot portion of the overshoe-boot which is of substantially conventional overshoe or galosh construction with the heel 7 and forepart 8 of suitable shape to accommodate the type of shoes over which the overshoe-boot is intended to be worn, the illustrated structure having a high heel for high heel shoes commonly worn by women.

It is to be understood of course that the foot portion 6 of the overshoe-boot may be of shapes different than that illustrated to conform to the particular types of shoes over which the overshoe-boot is intended to be worn and that while

the overshoe-boot illustrated is of a ladies' type, the invention is not limited thereto.

As is customary in waterproof footwear the bottom of the overshoe-boot, including the sole, heel, and shank are of rubber of suitable thickness and suitably reinforced in the usual manner and the upper which is indicated generally at 9 comprises a lining 10 with an outer covering 11 of rubber thereon.

The foot portion 6 of the upper, which is generally reinforced at the toe and around the sole and around the heel and up the back in the usual manner is shaped so that when the foot and shoe are inserted therein it will cling thereto sufficiently to remain in place, whereas the portion of the upper 9 above the foot portion, is circumferentially continuous and sufficiently large and loose somewhat like an ordinary rubber boot, as shown in Fig. 1, so that the foot and shoe thereon may be readily inserted into the overshoe-boot.

This upper 9 which, as shown in Figs. 1 and 2, is preferably of approximately the height of the upper of conventional overshoes and galoshes, while preferably light and flexible as pointed out hereinafter, is sufficiently self sustaining so that it will remain upright when the foot and leg of the wearer are inserted therein and may be worn as it is shown in Fig. 1 as a loose top boot.

However, the front of the loose, flexible upper 9 is so constructed that it will fold readily as shown in Fig. 2 to a form fitting form in which it fits snugly and neatly over the instep and around the lower portion of the leg of the wearer, and a tab 12 with fastener is arranged at approximately the juncture of the instep and lower leg portions, as shown in Fig. 2 to hold the upper 9 in this folded manner so that the overshoe-boot may be worn as a neat, close fitting overshoe or galosh when desired.

The tab 12 is permanently secured at the end 13 thereof to the upper 9 at an appropriate place to overlie the fold and the opposite end 14 of the tab is provided with a fastener for attachment to the upper beyond the fold. This fastener is preferably of the conventional snap fastener type with the female element 15 thereof on the tab 12 and the male element 16 being preferably small and of the same color as the upper 9 so that it is inconspicuous when exposed, as it is when the overshoe-boot is worn as a loose fitting boot as in Fig. 1.

For holding the loose end of the tab 12 in place when the overshoe-boot is in normal loose fitting boot form of Fig. 1, another male fastener element 17 is provided on the upper 9 with which the female element 15 is engageable, and the arrangement of the tab 12 is such that when engaged with the fastener element 17, the tab 12 is centrally disposed across the front of the upper and has the appearance of a decorative feature of the boot.

This tab 12 may have a decorative covering such, for example, as a crystal ornament 18 over the female fastener 15 to add to the attractiveness of the overshoe-boot and the tab itself is preferably of ornamental form so as to constitute a decorative and attractive feature of the overshoe-boot in both the loose fitting and snug fitting forms thereof. Obviously a variety of arrangements of ornamental or decorative types may be employed in place of the disclosed tab 12 as, for example, it may be in the form of a bow or an ornamental buckle may overlie the tab 12 or even be used as the fastening means itself in place of the tab and snap fastener.

To facilitate the folding of the upper at the selected place at the front of the overshoe-boot the upper is formed with an inherent acute angled bend 19 extending up the front from a point substantially at or slightly above the base of the instep to the top of the foot and this inherent bend 19 is of such a nature that when the tab 12 is pulled over to snap on the fastener element 16, the upper folds naturally along the bend 19 and lays neatly and compactly down against the side of the upper as indicated at 19a in Figs. 2 and 4. Moreover, this inherent bend 19 tends to some extent to hold the loose upper in upright position and gives to the upper a creased front appearance that is more pleasing and attractive than an ordinary rounded upper.

As a further means to facilitate folding of the upper at the selected place, and at the same time impart attractiveness to the overshoe-boot, the top of the overshoe-boot is notched as at 20 at opposite sides of the front at the place where the folded front doubles back against the side of the upper so that the upper tends to double back at the place where the notches are deepest and there is accordingly less length of stock to be bent. Preferably also the top of the boot is curved gracefully downward at each side to the respective notch as indicated at 21 and beyond the notches 20 the boot front tapers upwardly somewhat to a point 22 which is at a lower elevation than the main portion of the boot top so that it folds back against the side of the upper and substantially below the top thereof as shown in Fig. 2, and by reason of this notch 20, curve 21, and front point 22 construction, the overshoe-boot not only has a unique and attractive top in the loose fitting boot form but in the folded close fitting form has a sort of collar like top with V-front which is desirable not only for its pleasing appearance but for comfort as well.

Obviously the upper and especially that portion thereof where the folding occurs should be relatively thin and flexible so as to fold readily and avoid bulkiness. Preferably the entire upper, including the foot portion thereof, is relatively light weight, thin, and flexible with only such reinforcing as is necessary for strength and stiffening where and to the extent required so that the upper will fit neatly, fold readily and permit freedom of movement without chafing or discomfort. Preferably also the entire upper is stretchy so as to accommodate some variations in size of the shoe and leg on which it may be worn and insure a neat snug fit.

Such an upper may be made by using a lining 10 of knitted fabric such as stockinet arranged to stretch most readily in a direction circumferentially of the upper and which, because of its loose texture may be shaped quite readily to the overshoe-boot shape including the foot portion thereof, and this lining is covered with a stretchy layer 11 of rubber so that the composite lining and rubber which is relatively thin and quite flexible, stretches quite readily and thus may be distended if necessary in inserting the foot and shoe into the overshoe-boot and fits snugly on the inserted shoe so that the overshoe-boot is retained securely in use.

Footwear of this character is commonly made on a last, the lining, rubber surfacing, sole, heel, reinforcements, etc., being assembled thereon after which the assembled structure is vulcanized while remaining on the last.

For the illustrated overshoe-boot a last is employed which as heretofore indicated is tapered at

the front to form an angular ridge 23 extending up the front from approximately the base of the instep or somewhat thereabove to the top of the last so as to form the acute angular bend 19 at the front of the overshoe-boot, and the stretchy lining is applied on this last and lasted over an insole in the usual manner after which the reinforcements are applied and the overshoe-boot completed thereon in the usual manner and vulcanized, the tab 12 being also preferably secured at its end 13 to the assembled overshoe-boot at the time so that it becomes vulcanized thereto. Preferably the tab 12 is secured to the upper 9 throughout the entire end portion 13 thereof up to the bend 19 so that it is loose only at and beyond the bend 19, as this arrangement tends to localize the folding at the bend 19.

The rubber surfacing 11 may be calendered onto the lining material 10 before the latter is assembled on the last, as is well known in the industry, a relatively thin rubber surfacing preferably being employed, or the lining with the insole and reinforcements may be assembled on the last and the rubber surfacing 11 then applied on the assembled lining by dipping the assembly in a rubber dispersion or by spraying the rubber dispersion thereon as is also well known in the rubber industry.

A rubber finishing strip 23 is preferably applied around the top of the overshoe-boot before vulcanization, and the fastener element 15 may be applied to the tab and the fastener elements 16 and 17 to the upper, either before or after vulcanization as desired.

In galoshes and overshoes of form fitting type as commonly made, the upper is slit or divided to provide an expansion opening so that the upper may be expanded for inserting the foot, and an expandible bellows like closure is usually provided for this opening and folds together at the inside of the upper when the expansion opening is closed together in the form fitting form in which it is intended to be worn.

Thus in conventional galoshes and overshoes the upper is not circumferentially continuous but is divided at the expansion opening and such galoshes or overshoes are not adapted to be worn in a loose manner as they are unsightly and uncomfortable unless closed. Moreover, the expansion opening of such galoshes and overshoes is difficult to seal satisfactorily and is oftentimes the source of leakage.

With my present construction, however, the upper is circumferentially continuous with no opening, insert, or the like which are likely to be a source of leakage, and accordingly the upper is completely waterproof in both the folded and non-folded forms. Moreover, because of the continuous unbroken upper, it is neat and attractive in the loose, unfolded form and accordingly may be worn in that manner as a loose fitting boot or it may be folded and worn as a snug fitting galosh or overshoe in which form it also has a neat attractive appearance.

While I have shown and described my invention in a preferred form, I am aware that various changes and modifications may be made therein without departing from the spirit of the invention, the scope of which is to be determined by the appended claim.

What is claimed is:

A bootee with a thin, flexible, elastically stretchy upper and having a snug elastically stretchy form fitting foot portion by which the bootee is securely held on the foot of the wearer, the portion of the upper above said foot portion being circumferentially continuous and loose fitting to admit the foot therethrough and foldable at the front along the instep and thereabove to snug fitting form, and means attached to the foldable portion at the upper end of the instep for folding said portion laterally against the front of the bootee and detachably fastenable to the bootee to hold said portion in snug fitting laterally folded position, said foldable portion having laterally spaced notches at the top where it folds laterally against the front of the bootee.
